UNITED STATES PATENT OFFICE.

WILLIAM C. METZNER, OF CHICAGO, ILLINOIS.

STOVE-GRADE.

SPECIFICATION forming part of Letters Patent No. 401,508, dated April 16, 1889.

Application filed May 16, 1887. Serial No. 238,307. (No model.)

To all whom it may concern:

Be it known that I, WILLIAM C. METZNER, a citizen of the United States, residing at Chicago, in the county of Cook and State of Illinois, have invented certain new and useful Improvements in Stove-Grates; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to stove-grates, and has reference particularly to what are known as "basket-grates" for cooking-stoves.

The object of the invention is to provide a basket-grate adapted to be adjusted as to size 20 to fit stoves of different sizes.

In the accompanying drawings, Figure 1 is a plan of the grate having the end walls removed. Fig. 2 is a rear elevation. Fig. 3 is an end elevation. Fig. 4 is an end elevation 25 having the end wall removed. Fig. 5 is a transverse vertical section in line $x x$ of Fig. 1. Fig. 6 is a section in line $y y$ of Fig. 1. Fig. 7 is a detail of the lower ends of the plates forming the end walls.

30 The principal parts of the grate are the overlapping sections A and B and the end walls, D D. The section A forms the front and a portion of the bottom of the grate, and the lower half of the front and the bottom 35 portion thereof are composed of transverse ribs A^2 , the upper half of the front remaining a solid part, A^3 . The section B is applied to either the lower or the upper face of the rear portion of the section A in such manner as to 40 adapt it to be moved backward or forward with reference to the section A, to increase or decrease the width of the grate, as will be hereinafter described. The end walls, D, may also be made adjustable as to dimensions, 45 and they may be adapted to be shifted on the sections A and B to vary the length of the fuel-chamber.

The sections A and B may have combined with them a section, forming a part of the bottom, capable of being shaken or of being dumped, or which embodies both the shaking

and dumping features. The drawings show such a section having the latter construction, and such section is herein termed the "dump."

The extension-section B is shown applied to 55 the bottom of the rear portion of the section A, and provided with ribs b , corresponding to the ribs A^2 in the section A. Bolts B' , passing between the ribs A^2 and b , bind said sections B and A together, (see Figs. 1 and 7,) 60 and said bolts may be moved between said ribs to allow the section B to be moved backward and forward horizontally beneath the section A, said section B forming a portion of the bottom of the grate, and adapt said bottom to be changed in width. To give said section B greater strength and to level the rear of the grate, the rear margin of said section may be cast with a flange, B^2 , rising behind the rear margin of the section A even 70 with the upper surface of the latter. B^3 are short legs projecting downwardly from the bottom of the section B. Upon these the rear portion of the grate is supported when in the stove.

75 Fig. 1 shows the ribs A^2 cut away at the middle of the horizontal portion of section A, thus forming the central opening, A' , and at one end of the section A the upper faces of all the ribs A^2 and at the opposite end at 80 least the rib next to the opening A' are provided with concave recesses a^2 to receive the journals of the dump, which I next describe.

C is a dump occupying the opening A' and having its upper surface on a level with the 85 horizontal part of the section A, and having ribs c to correspond with the ribs A^2 and b .

C' and C^2 are horizontal journals extending outwardly from the ends of said dump, parallel with the sides of the section A and a 90 little forward of the middle of said dump. Said journals lie in the recesses a^2 of the section A, and upon them the dump C may be partially rotated. The rear portion of said dump extends over the section B, and since 95 the journals C' and C^2 are forward of the middle of said dump, the portion of the latter at the rear of said journals will have a preponderance of weight over the portion at the front of said journals, and will therefore lie 100 upon the plate B, excepting when tilted forward to dump the ashes and cinders. The

outer end of the journal C' is made to extend a little beyond the edge of the section A, and has the sides of such end cut away or otherwise shaped to receive a wrench or other tool 5 by which to turn the dump in a forward direction and empty the material upon the grate into the ash-receptacle below, as has been done heretofore in other grates.

Upon the upper side of the outer end of the 10 journal C' stands a post, c', while upon the adjacent part of the section A stands a similar post, c². These are to be engaged by the eyes c³ of a shaker, C³. (Shown in the drawings.) By moving said shaker to and fro 15 horizontally the dump is reciprocated lengthwise, the post c² forming a fulcrum for the movement of the shaker and the dump C being enough shorter than the opening A' to allow the desired movement of the dump. This 20 reciprocal movement of the dump I term the "shaking," while I term the rotation of it the "dumping." Both of these operations are old.

D D are the end walls, and they are composed of the plates D' D², overlapping and 25 held together by a bolt, D³, passing through a hole, d', in the plate D', and a horizontal slot, d², in the plate D². That portion of the plate D² which is opposite the part A³ is shaped to fit closely against the latter, while 30 immediately beneath said part A³ said plate D² extends forward between the outermost ribs, A², and forms a hip, d³, which engages the lower edge of the part A³. From the corner of the plate D², beneath said hip d³, a leg, 35 D⁴, extends downwardly between the ribs A² even with the lower ends of the legs B³ on the plate B. The rear portion of the grate is thus supported upon the feet B³, while the front thereof is supported upon the feet D⁴. The 40 lower edges of the plates D' and D² are preferably extended into the space between the ribs A² and the pair of such plates standing over the journal C', provided with the oblong notches d⁴ d⁵ to make room for said journal. The 45 lower rear corner of each of said plates D' rests upon the upper surface of the horizontal portion of the grate. As will be readily seen by the drawings, each plate D² may be moved backward or forward when the bolts D³ are 50 loose. The end walls, D D, may thus be made to conform to the width of the bottom of the grate. To provide for the further adjustment of the size of said walls, the free edges thereof may have the parallel breaking-grooves d⁶, as 55 shown in Fig. 3, said grooves facilitating the breaking of such edges to reduce the size of the plates.

In order that the length of the grate may also be reduced, the outer ends of the part A³ 60 and the rear edge of the section A are provided with transverse breaking-grooves a³, arranged in line with the spaces between the ribs A², while the front and rear edges of the plate B are provided with similar grooves, b². 65 By means of these grooves the outer ribs, A² and b, may be broken away. When this has been done, the walls D are seated between

the then remaining outermost pair of ribs. These grooves may be formed at one or both ends of the grate, and may be multiplied so 70 that any desired number of ribs A² may be broken away. When the aforesaid breaking-grooves are formed at the end at which the journal C' is located, a corresponding number of the adjacent ribs A² must be provided 75 with posts c², to the end that such a post may remain after the grate has been reduced. When more than one such post remains after the grate has been fitted to the stove, all except the outermost may be broken off. 80

In order that the journal C' may be correspondingly shortened, it is provided with suitably-spaced breaking-grooves, c⁴, and additional posts, c', all except the outer of said posts remaining after the grate has been fitted 85 to the stove being broken away. These breaking-grooves are not in themselves new.

The section A and dump C may be used without the section B when the section A is wide enough to fill the space in the fire-chamber of the stove, and end plates different from the one shown herein used therewith. In such a case a web corresponding to the middle portion of section B is to be extended across the opening A', beneath the rear end of the 90 dump C, to support the latter. As such web is to occupy the position of the middle portion of said section B, and may be of the same form, I deem it unnecessary to illustrate the same separately in the drawings; and a section, A, having no dump, but having fixed ribs over its entire bottom, may be used in combination with the end walls, D, set between the outer pairs of ribs, A², and forming a support for the front of the section A. In each 100 of these cases the breaking-grooves may be provided to facilitate the reduction of the length of the grate.

I claim as my invention—

1. In a stove-grate, the combination, with a 110 section having an upright part to form the front of the fire-pot and a horizontal part to form the bottom thereof, of a horizontally-adjustable section overlapping the first-named section and end walls composed of adjustable 115 overlapping plates set between the ribs of said sections, substantially as shown and described.

2. In a stove-grate, the combination, with a 120 section having an upright part to form the front of the fire-pot and a horizontal part to form the bottom thereof, of a horizontally-adjustable section overlapping the first-named section and end walls composed of adjustable 125 overlapping plates set between the ribs of said sections, said second section having legs to support the rear of the grate and the front plates of said end walls being each provided with a supporting-leg and a hip or its equivalent, by which it engages said first-named section and supports the latter, all substantially 130 as shown and described.

3. In a stove-grate, a section, A, having an opening, A', and recesses a² in the ribs A² at

each end of said opening A', a dump, C, lying in said opening and having its journals resting in the recesses a^2 , the ends of the section A being provided with breaking-grooves to facilitate the breaking away of the outermost ribs, A ^{2} , substantially as shown and described.

5 4. In a stove-grate, the combination, with a section, A, having the transverse ribs A ^{2} , of end walls, D, having a hip and leg at the front side and seated between said ribs and supporting the front of the section A, while the rear of said section is provided with supports, as legs B ^{3} , independent of said end walls, substantially as shown and described.

10 5. In a stove-grate, the combination, with a

section, A, having the transverse ribs A ^{2} , of end walls, D, having a hip and leg at the front side and seated between said ribs and supporting the front of the section A, while the rear of said section has applied to its lower 20 side a section, B, from which depend legs whereon the rear of the grate is supported, substantially as shown and described.

In testimony whereof I affix my signature in presence of two witnesses.

WILLIAM C. METZNER.
